UNITED STATES PATENT OFFICE

158,035

COMBINED FLASHLIGHT, COIN, KEY, AND CARDHOLDER

Victor L. Anderson, District Heights, Md.

Application September 13, 1948, Serial No. 148,560

Term of patent 3½ years

(Cl. D48—27)

To all whom it may concern:

Be it known that I, Victor L. Anderson, a citizen of the United States, residing at District Heights, in the county of Prince Georges, and State of Maryland, have invented a new, original, and ornamental Design for a Combined Flashlight, Coin, Key, and Cardholder, of which the following is a specification, reference being had to the accompanying drawing, forming part thereof.

Figure 1 is a perspective view of a combined flashlight, coin, key, and cardholder showing my new design,

Figure 2 is a top plan view thereof, and

Figure 3 is an underside plan view of the same.

I claim:

The ornamental design for a combined flashlight, coin, key, and cardholder, as shown.

VICTOR L. ANDERSON.
